UNITED STATES PATENT OFFICE.

SPENCER C. CARY AND VINCENT RAGONA, OF BROOKLYN, NEW YORK, ASSIGNEES, BY DIRECT AND MESNE ASSIGNMENTS, TO CARY MANUFACTURING COMPANY, OF BROOKLYN, NEW YORK, A CORPORATION OF NEW YORK.

MEANS FOR BINDING SHIPPING-PACKAGES.

1,350,137.

Specification of Letters Patent. Patented Aug. 17, 1920.

Application filed March 9, 1918. Serial No. 221,571.

To all whom it may concern:

Be it known that we, SPENCER C. CARY and VINCENT RAGONA, both citizens of the United States, residing at the city of New York, borough of Brooklyn, county of Kings, and State of New York, have invented a certain new and useful Means for Binding Shipping-Packages, of which the following is a specification.

10 This invention is a device for applying a tie or binder to a shipping package, such as a box, case, shoo, crate, or the like, the object in view being to attain economy of time and labor in placing the binder or tie around the package preliminarily to the operations of stretching said binder to secure the required tension thereon and of fastening or sealing said binder or tie.

15 The invention is useful, more particularly, in positioning a binder upon packages of predetermined size in business establishments where large numbers of such packages are required to be tied or bound, although provision is made in said device for 20 changes in the relation of the work-locating means and of the binder-bending jaws so as to adapt the device for use in applying bands or ties to packages which may 25 vary in size within certain limits of dimensions.

30 According to this invention, a tie or binder is first placed in position with respect to means for determining the location of the package, and after the package is positioned, said binder or tie is bent upwardly at two points and in a manner to fit snugly to the under side and to the opposite walls of the package and to the two lower corners thereof. The upward bending 35 of the binder or tie is performed simultaneously in order to facilitate the work, and said binder or tie in a bent condition is retained snugly into contact with the package during the operations, subsequently 40 performed, of stretching the tie in a taut condition around the package and of securing and anchoring the free or loose ends of said tie.

45 Broadly speaking, the invention embodies 50 a plurality of tie-bending members in the form of jaws which are movable relatively to certain work-locating devices, for the purpose of bending a tie around the two lower corners of a package, it being pre-

ferred to so control the members or jaws 55 that they perform the added function of means for retaining the tie into contact with the respective sides of the package during the subsequent operations of stretching said tie, and of securing or anchoring the same. 60

65 In a practical form of the invention, the work-locating devices are embodied as a table and a gage, the latter being in spaced relation to said table. Said bending members or jaws are attached to a carrier in the form of a bar, said jaws being movable with said bar and being shiftable thereon to different operative positions. The bar carries, also, means for holding a tie, said tie-holders and the bending jaws being all movable 70 with the bar. For imparting movement to the bar, and the jaws and the holders thereon, it is preferred to use a foot treadle having an operative connection with said bar. In one form of the device, a latch is positioned 75 for locking engagement with the treadle so as to retain the bar and the bending jaws in their raised operating positions.

80 Other features and advantages of the invention will appear from the following description, taken in connection with the drawings, wherein—

85 Figure 1 is a view in front elevation of our device, certain parts being broken away and in section, said figure illustrating in full lines the position of one package and of the tie wire before bending the latter, and the dotted lines showing the positions of the parts and of the tie wire after bending the latter. 90

95 Fig. 2 is a plan view of the device, the table being partly broken away.

Fig. 3 is a vertical section on the line 3—3 of Fig. 1.

Fig. 4 is a cross section on the line 4—4 of Fig. 1. 100

Fig. 5 is an enlarged detail sectional view of one jaw showing the method of bending a tie wire around one corner of the shipping package.

Fig. 6 is a plan view of one tie holder.

Fig. 7 is a vertical section on the line 7—7 of Fig. 1 illustrating the other tie holder.

105 A designates a table supported by legs *a* at a height suitable for the operator, upon which table the package to be bound or tied is placed, said package being indicated by full lines in Fig. 1 by the reference

character X, and by dotted lines in Fig. 2. As shown, said table is provided at one edge thereof with a longitudinal metal rail B, preferably of the channel form shown in Fig. 3, said metal rail being attached in any suitable way to the marginal portion of the table. A gage bar C extends longitudinally of the rail B and is spaced relatively thereto by a spacer block e, said gage bar and the spacer block being attached rigidly to the metal rail. The gage bar is positioned in the path of a package which is adapted to be placed upon the table and the metal rail, and which package is slid over the table against the gage bar C, said parts constituting the work-locating devices.

The gage bar supports one or a plurality of stops D, the latter being slotted as shown in Fig. 3 so as to fit upon the gage bar and to slide lengthwise thereon, said stop being fastened at a suitable point on the gage bar by a clamping screw d which is mounted in the stop and is adapted to bind against the bar. It is apparent that the bar is positioned for contact with one side of the package adapted to be placed upon the table and the rail, whereas the stop is located for contact with another side of the package whereby the position of the package with respect to the bending devices may be located with precision.

E, F are bending jaws, and G is a carrier therefor, with which carrier is associated mechanism for imparting movement to the carrier and the jaws whereby the latter act in bending a binder or tie at two points around the package X. In the form of the invention illustrated the carrier G is a horizontal bar positioned at a suitable distance below the plane of the table and the metal rail. This bar extends a suitable distance crosswise of the table and, preferably, beyond the marginal portions thereof. The bending jaws are carried by the bar G and they are slidable relatively to the work-locating devices. Said jaws E, F are vertically positioned and are adapted for slideable movement in vertical planes. The jaws slide through slots e provided in the metal rail B, and in the normal position of the carrying bar G said jaws extend above the slots for a suitable distance, as shown in Figs. 1, 3 and 4 of the drawings. Each jaw consists of a metal bar provided at its lower portion with a loop e' and with a binding screw e², said loop of the jaw embracing the bar G. The loops of the jaws are movable relatively to the bar G in the direction of the length thereof, and said jaws E and F are retained in the positions to which they are shifted by setting the screws e² into binding contact with the bar G, whereby the jaws E and F are adjustable on the bar and with respect to the work-locating devices so as to adapt the machine to operate

upon packages X which vary in length. The slots e in the rail B should be sufficiently long to accommodate the adjustment of the jaws E and F. Each jaw is provided, furthermore, with a slot f in its upper end portion and with a groove f' in that face or edge of the jaw which lies next to the package X, whereby the jaw is adapted for contact with the binder or tie in a manner to bend said binder or tie around the lower corner of the package.

H is a fixed standard provided at its lower part with a footpiece h, and at its upper part with the horizontal arm h'. The footpiece is intended to be secured to the floor, and the arm is attached to the under side of the table A and the rail B. Against one face of this standard is fitted a vertically movable slide I, the same being provided with longitudinal slots i, through which pass bolts i' attached to the standard, whereby the slide I is limited to reciprocating movement in a vertical direction. The upper part of the standard I is united to, or made fast with, the carrier bar G by any suitable mechanical means, whereby the slide and the bar are coupled rigidly for vertical movement.

As a means for conveniently operating the slide I and the bar G, we employ a treadle J pivoted at j to a short post J'. This treadle is provided at one end with a footpiece j', the other end of the treadle being pivotally or loosely connected by a pin j² with the slide I. The pressure of the foot upon the treadle J depresses one end of the treadle and lifts the other end so as to move the slide I and the bar G upwardly thereby imparting sliding movement simultaneously to the jaws E and F, but when the foot pressure is removed, the weight of the parts lowers the bar, the jaws and the slide to their normal positions.

It is desirable to retain the jaws E and F in their raised positions in order that said jaws may hold the upstanding lengths of the binder or tie into contact with the ends of the package X during the operations of stretching the binder or tie and securing the end portions thereof. Accordingly, we provide means for locking the slide, the bar and the jaws when raised, said means consisting, preferably, of a latch K pivoted at k and provided with a shoulder k' adapted to fit over the upper edge of the treadle J. Said latch carries a spring L which is in contact with a pin l, and when the treadle is depressed to the dotted line position of Fig. 1, said spring acts to force the latch K in a direction for the shoulder k' to snap over the upper edge of the treadle, whereby the latch locks the treadle in its depressed position, see Figs. 1 and 3.

It is desirable to use a binder or tie in a straight flat condition and of a length to ex-

tend around the four sides of the package so that the end portions of the binder or tie will overlap a distance of two inches, more or less, in order that said end portions may be anchored or fastened. The rail B is positioned slightly below the top surface of the table so that the anchor or tie indicated at Y may rest upon said rail below the package. As a means for holding the tie, we employ 5 two holders M N positioned at opposite sides of the table A, and bending jaws E and F. As shown, said tie holders M and N are supported by the bar G on the opposite end portions thereof, but it is apparent that these tie holders may be supported in any other 10 desired manner. The tie holder M is provided with a loop m which is secured to an upstanding bar m', the latter having a loop o and a binding screw o', so that the holder 15 M may be fastened adjustably to one end portion of the bar G. The holder is provided with a flared mouth portion p the lower side of which is closed by a plate p', whereby an end portion of the tie Y may 20 be easily introduced into the holder M, see Fig. 6. The other holder N is forked at its upper end to provide the crotch q, said holder being provided at its lower portion with a loop q' and a binding screw q', said 25 loop and the screw affording means for clamping the holder N to an end portion of bar G.

The operation is as follows:—

A binder or tie of the required length, 30 such as Y, is positioned upon the rail B and within the slots f of the jaws E and F so that one end of said binder or tie is within the holder M and extends through the holder N, see Fig. 1. A package, such as X, is 35 placed upon the table and moved over the rail B and into contact with the gage bar C and the stop D. The operator presses upon the treadle J, thereby elevating the slide I, bar G and jaws E and F, and upon the descent of the treadle to a predetermined position, latch K snaps over said treadle so as to lock the slide, the bar and the jaws in their raised positions. The upward movement of the jaws bends the binder or tie at 40 two points and around the two lower corners of the package, the jaws sliding relatively to the end portions of the tie or binder, and the grooves f' of said jaws receiving the binder or tie, whereby the jaws when locked 45 in their raised positions operate to retain the bent portions of the binder into close relation to the opposite sides of the package, as indicated by dotted lines in Fig. 1. The jaws hold the binder in position and in contact with the package during the subsequent 50 operations of bending the free portions of the binder over the top of the package, of stretching the binder so as to draw it into tight engagement with the package, and of 55 anchoring the end portions of the binder 60

in order to complete the operation of binding or tying up the package. The operator presses against the latch in order to disengage the shoulder from the treadle and the weight of the slide, the bar and the jaws 70 returns the parts to their normal positions, thereby withdrawing the jaws from contact with the package and permitting the latter to be moved easily from the table.

It should be noted that the gage and the 75 stop are so related to the jaws that the package is located in a proper position for receiving the binder, whereby the binders may be applied to all the packing cases at a predetermined distance from the ends of 80 said packing cases.

It is apparent that certain elements of the device are adjustable to accommodate packages of different sizes, and that said device enables an operator to quickly position the 85 binders into contact with the packages so as to facilitate the operation of applying the binders and to save time and labor in performing the necessary operations.

Having thus fully described the invention, 90 what we claim as new and desire to secure by Letters Patent is:

1. In a device for applying binders to shipping packages, the combination with a table, and work-locating devices thereon, of 95 a carrier bar movable relatively to said table, a plurality of bending jaws mounted on said carrier bar for movement therewith, said bending jaws being slotted for the reception of a binder and said jaws being 100 grooved for the reception of said binder after the latter shall have been bent relatively to a package, and means for imparting movement to the carrier bar and the bending jaws relatively to the table. 105

2. In a device for applying binders to shipping packages, the combination of a table provided with slots, and work-locating devices adjacent said slots, of a horizontally positioned carrying bar movable relatively 110 to said slotted table, a plurality of bending jaws mounted on said carrying bar for movement therewith, said bending jaws being slidable within said slots of the table, means separate from the bending jaws for receiving and locating a binder in a desired position across said table, and means for imparting movement to said carrying bar whereby the bending jaws are moved vertically with respect to the plane of the table. 115

3. In a device for applying binders to shipping packages, the combination with a slotted table and package-locating devices adjacent said slot, of a horizontally positioned carrying bar movable relatively to 120 said table, a plurality of bending jaws fixedly attached to said carrying bar and extending upwardly therefrom for sliding movement within the slotted part of said table, said bending jaws being grooved and 125

adapted to receive a binder subsequent to the operation of bending said binder with respect to the package, means for imparting movement to said carrying bar, and 5 means for locking the carrying bar and the bending jaws in raised positions.

4. In a device for applying binders to shipping packages, the combination of a table, a slotted rail fixed to said table for 10 the top surface of the rail to lie in a plane below the top surface of the table, said rail being provided with package-locating means, a horizontally-positioned carrying bar below the rail and movable relatively to the 15 table, a plurality of bending jaws mounted on the carrying bar and extending upwardly therefrom for sliding movement with respect to the slotted rail, and means for imparting movement to said carrying bar and the bending jaws. 20

5. In a device for applying binders to shipping packages, the combination with a slotted table, and work-locating devices thereon, of a plurality of bending jaws slideable relatively to said slotted table, said bending jaws being notched for the reception of a binder and said jaws being provided on their opposing faces with grooves adapted to receive the binder subsequently 25 to the operation of bending the binder relatively to a package, means for imparting to the jaws a sliding movement with respect to said table, and means for locking and releasing said jaws so that when locked the 30

grooved faces of the jaws retain the binder 35 in a bent condition and in contact with a package.

6. In a device for applying binders to shipping packages, the combination with a slotted table, and work-locating devices 40 thereon, of a carrying bar positioned below said table and movable relatively thereto, a plurality of bending jaws attached to said bar for movement therewith with respect to the slotted table, said bending jaws being 45 notched for the reception of a binder, means whereby one jaw may be adjusted on the carrying bar with respect to the other jaw, and means for imparting movement to said carrying bar and the bending jaw. 50

7. In a device for applying binders to shipping packages, the combination with a table, and work-locating devices thereon, of a carrying bar positioned below said table, a plurality of bending jaws attached to said 55 bar and extending upwardly therefrom for sliding movement with reference to said table, a plurality of binder-holders separate from the bending jaws and mounted on the carrying bar for movement therewith, and 60 means for imparting movement to the carrying bar.

In testimony whereof we have hereunto signed our respective names this 8th day of March 1918.

SPENCER C. CARY.
VINCENT RAGONA.
